UNITED STATES PATENT OFFICE.

LUDWIG DÜRR, OF FRIEDRICHSHAFEN, GERMANY, ASSIGNOR TO THE FIRM LUFT-SCHIFFBAU ZEPPELIN, GESELLSCHAFT MIT BESCHRÄNKTER HAFTUNG, OF FRIEDRICHSHAFEN, BODENSEE, GERMANY.

AIRSHIP.

Application filed August 16, 1923. Serial No. 657,834.

To all whom it may concern:

Be it known that I, LUDWIG DÜRR, citizen of the German Empire, residing at Friedrichshafen, on the lake of Constanze, Germany, have invented certain new and useful improvements in Airships, of which the following is a specification.

Rigid airships are constructed of cross members and longitudinal girders, braced by wires. It has become usual to stiffen this frame work in its longitudinal direction by adding a kind of keel. For this purpose the lower part of the gas enveloping hull is developed to a special truss frame of triangular or other form of cross section. Heretofore this keel has been arranged underneath the gas enveloping frame so that two longitudinal girders of this frame were the upper part and a third girder—added for this special purpose—was the lower part of the keel truss frame. Posts were arranged between these three girders, lying in the vertical plane, and all of them were braced by wires. This triangular keel ran from stem to stern and was used as a passage. In this passage a part of the useful load of the airship was disposed, for example gasoline tanks, ballast tanks, bombs and so on. The keel served to distribute these weights to the cross members or rings of the big frame work. So the height of such an airship was equal to the diameter of the ship plus the height of the gangway or keel.

Furthermore it has become known to turn this keel and gangway upside down and transfer it at the same time inside the circumscribed circle of the cross section of the gas enveloping frame. The reason was to diminish the total height of the ship.

My invention now is to arrange this keel partly inside partly outside the circumscribed circle of the cross section of the gas enveloping frame. The advantage is that by this way, it will be possible to have the benefit of the steady and stabilizing effect of the outer keel in a desirable degree and on the other hand to let the keel disappear inside the enveloping frame to such extent as seems suitable with regard to the ship's height.

As described before, it has been usual to mount the keel on one beam or one side of the polygon forming the cross member or ring. According to my invention it will be

possible to mount it for example on two adjoining beams, whereby it will become much stronger and at the same time allow more room for the purpose as gangway.

The accompanying drawings will explain my invention. Fig. 1 is a longitudinal view of an airship without outer cover. Fig. 2 is a cross section of the same on a larger scale. Fig. 3 to 6 are constructional modifications of the keel according to the present invention. Fig. 7 is a plan of Fig. 5.

In Fig. 1 to Fig. 6 is shown how the keel gangway is disposed partly outside partly within the circumscribed circle of the cross section polygon. *x* is the upper line, *y* the lower line of the keel gangway *A*, while *z* is the lower line of the shape of the main frame work. In Fig. 2, 5 and 6 the triangle *a b z* comprises two sectors of the cross section polygon, *a b* being the base of the keel gangway.

In Fig. 7 the rings are marked *e*, the normal longitudinal girders *i*, the longitudinal girders especially for the keel gangway *k*; *f* are ties and *g* braces.

It should be understood that I do not desire to be limited to the exact details of construction shown and described, for obvious modifications will occur to a person skilled in the art.

What I claim is—

1. A rigid airship, comprising a tubular rigid hull of substantially polygonal cross section, a reinforcing rigid keel of substantially polygonal cross section, said keel replacing a portion of the wall structure of said hull, and being situated partly inside and partly outside of said hull.

2. A rigid airship comprising a circumferential frame structure extending longitudinally of said airship and having a substantially polygonal cross section, a portion of said frame being developed into a reinforcing keel structure also extending longitudinally of said airship, the cross section of said keel projecting inwardly into the space confined by said circumferential frame and also outwardly from a circle circumscribed around said circumferential frame, said keel constituting a longitudinal passage inside of said airship.

3. A rigid airship, comprising a hull, the cross section of said hull having a substantially polygonal shape with a substantially

convex circumference, a reinforcing structure at the circumference of said hull and formed integral therewith, said reinforcing structure extending longitudinally of said airship and constituting a keel and having a longitudinal passage, the cross section of said reinforcing structure projecting in-

wardly into the space confined by said hull and outwardly from the circle circumscribing the polygonal cross section of said hull. 10
Signed at Friedrichshafen (Bodensee) this 18th day of June, 1923.

LUDWIG DÜRR.
